(57) **CLAIM**

I claim the ornamental design for a separation tool, as shown and described.

DESCRIPTION

FIG. 1 is a front perspective view of a first embodiment of a separation tool;

FIG. 2 is a back view thereof;

FIG. 3 is a front view thereof;

FIG. 4 is a right view thereof;

FIG. 5 is a left view thereof;

FIG. 6 is a top view thereof;

FIG. 7 is a bottom view thereof;

FIG. 8 is a front perspective view of a second embodiment of a separation tool.

FIG. 9 is a back view thereof;

FIG. 10 is a right view thereof;

FIG. 11 is a left view thereof;

FIG. 12 is a top view thereof; and,

FIG. 13 is a bottom view thereof.

The portions of the article shown in broken lines form no part of the claimed design.
